(57) **CLAIM**

We claim the ornamental design for a vaporizer pod, as shown and described.

DESCRIPTION

FIG. 1 is a front (and identical rear) elevation view of the vaporizer pod, showing my new design;

FIG. 2 is a right (and identical left) elevation view thereof;

FIG. 3 is a top plan view thereof;

FIG. 4 is a bottom view thereof; and,

FIG. 5 is a top perspective view thereof.

The broken lines in the drawings depict portions of the vaporizer pod that form no part of the claim.
